UNITED STATES PATENT OFFICE

136,218

DESIGN FOR A MERCHANTISE CART

Jules V. Accardi and Garland E. Watts,
El Cerrito, Calif.

Application June 20, 1942, Serial No. 107,269

Term of patent 7 years

To all whom it may concern:

Be it known that we, Jules V. Accardi and Garland E. Watts, citizens of the United States and residents of El Cerrito, county of Contra Costa, State of California, have invented a new, original, and ornamental Design for a Merchandise Cart, of which the following is a specification, reference being had to the accompanying drawing, forming part thereof.

We claim:

The ornamental design for a merchandise cart, substantially as shown.

JULES V. ACCARDI.
GARLAND E. WATTS.
